(57) **CLAIM**

The ornamental design for a sauna stove tent, as shown and described.

DESCRIPTION

FIG. 1 is a perspective view of a new design for a sauna stove tent;

FIG. 2 is a front view thereof;

FIG. 3 is a right side view thereof;

FIG. 4 is a rear view thereof;

FIG. 5 is a left side view thereof; and,

FIG. 6 is a top view thereof.

The bottom view is not visible during use.

The broken lines shown in the drawings depict portions of the sauna stove tent that form no part of the claimed design.

1 Claim, 6 Drawing Sheets
